DESIGN FOR A FRONT PLATE FOR ELECTRIC ROOM HEATING UNITS

Albert J. D. Ohm, Buffalo, N. Y., assignor to Mar-
kel Electric Products, Inc., Buffalo, N. Y., a cor-
poration of New York

Application January 15, 1947, Serial No. 136,154

Term of patent 7 years

(Cl. D81—10)

To all whom it may concern:

Be it known that I, Albert J. D. Ohm, a citizen of the United States, residing at Buffalo, in the county of Erie and State of New York, have invented a new, original, and ornamental Design for a Front Plate for Electric Room Heating Units, of which the following is a specification, reference being had to the accompanying drawing, forming part thereof.

Figure 1 is a perspective view of a front plate for electric room heating units, embodying my new design.

Figure 2 is an elevation thereof viewed from either side.

Figure 3 is an elevation thereof viewed either from the top or bottom.

I claim:

The ornamental design for a front plate for electric room heating units, as shown.

ALBERT J. D. OHM.
